UNITED STATES PATENT OFFICE.

JAMES O'HARA, OF LEBANON, OREGON.

PAPER MACHINE.

1,420,135.

Specification of Letters Patent. Patented June 20, 1922.

Application filed October 3, 1919. Serial No. 328,131.

To all whom it may concern:

Be it known that I, JAMES O'HARA, a citizen of the United States, and residing at Lebanon, Linn County, State of Oregon, 5 have invented certain new and useful Improvements in Paper Machines, of which the following is a specification.

This invention relates to paper making machines and has particular reference to the 10 means for keeping the wire fabric, commonly called the wire, under tension or stress without subjecting it to such bending strains as will injure the fabric and cause early breakage. In devices of this kind, 15 such as the Fourdrinier paper machine, the wire passes over the table of the machine and around the breast roll at the end and back under the table, but in order to stretch and keep the wire under tension, it is made 20 to pass over supporting rollers and then under what is called a stretch roll, which is vertically adjustable to apply the necessary tension. This stretch roll serves the purpose of properly stretching the wire, but 25 it causes the wire to bend back and forth in its travel under the table and this results in crystallizing the wire, causing early breakage. According to my invention I do away with this stretch roll and the consequent bending of the wire, thus prolonging 30 its life, but at the same time I provide means for regulating the tension on the wire. According to my invention I use the breast roll itself as the means for stretching and tightening the wire. The novel features of my 35 invention will be apparent from the following description taken in connection with the drawings. In the drawings,

Fig. 1 is a plan view of a portion of a 40 paper making machine showing the breast roll and a part of the table; and

Fig. 2 is a side elevation of the same thing.

In the drawings 10 represents a part of 45 the well known frame of the paper machine which carries the table at its top made up of rollers, 11, as is usual. The wire 12 passes over the top of the table and then around the breast roll 13, and back under- 50 neath the table passing over roller 28, which merely supports it and holds it in straight horizontal position. In the form which I have shown the breast roll is not mounted in the main frame of the machine, but on 55 the bracket 14, secured to the frame by

bolts 15. It will be understood that there is one of these brackets at each side of the machine at the opposite ends of the breast roll, and each has in its top horizontal portion a grooved trackway 16 in which slides 60 a bearing block 17 which is made to properly fit in the groove. There is a slot 18 through the horizontal portion of the bracket through which projects a screw threaded part 19 extending downwardly 65 from the bearing block 17 and a nut 20 may be placed on the projecting screw threaded end to clamp the bearing block in desired position. The bearing block 17 has a vertical slot 21 in it, the bottom of which 70 is rounded to form a bearing for the shaft 22 of the breast roll. The bracket 14 has an upwardly extending portion 23 having a bearing 24 for the adjusting rod 25 provided at its outer end with the turning handle or wheel 26. The adjusting rod 25 is provided with screw threads at its inner end and they engage a screw threaded socket in the projection 27 on the bearing block 17. The adjusting rod 25 is mounted to turn 80 in the bearing 24 and to be held thereby against longitudinal movement because of the projecting shoulders on each side of the part 23, and it will be understood, therefore, that when this adjusting rod is turned, the 85 screw threaded engagement with the bearing block will move it longitudinally of the trackway 16. It will be understood that the operating mechanism is the same on both sides of the machine, and thus the breast 90 roll may be moved to any adjusted position longitudinally to stretch or tighten the wire to the desired extent. I wish it understood, however, that my invention is not limited to the particular means for adjust- 95 ing the breast roll, but the essential feature of my invention is the use of the breast roll as a means of tightening the wire thus doing away with the stretch roll and consequent bending of the wire.

Having thus described the invention what I claim as new and desire to be secured by Letters Patent is:

1. In a paper making machine the combination with a frame, of a table supported 105 thereby, a wire passing over said table, a breast roll supported by said frame at the end of the table around which said wire passes and means for adjustably moving said breast roll longitudinally of the ma- 110

chine to different adjusted positions as the sole means to stretch or put tension on said wire.

2. In a paper making machine the combination with a frame, of a table supported thereby, a wire passing over said table, a breast roll supported by said frame at the end of the table around which said wire passes, means for adjustably moving said 10 breast roll longitudinally of the machine to different adjusted positions as the sole means to stretch or put tension on said wire, and rollers below said table to support said wire leaving the lower part of the breast roll in a straight line without bends.

3. In a paper making machine the combination with a frame, of a table supported thereby, a wire passing over said table, a breast roll at the end of the table around 20 which said wire passes, bearings for said breast roll movable longitudinally of the machine as the sole means to stretch or put tension on said wire passing around said roll and means including an accessible hand controlled part for adjustably moving said bearings to secure the desired tension.

4. In a paper making machine the combination with a frame, of a table supported

thereby, in a single plane a wire passing 30 over said table, a breast roll at the end of the table around which said wire passes, bearings for said breast roll movable longitudinally of the machine as the sole means to stretch or put tension on both the upper 35 and lower portions, said wire passing around said roll manually operable, means for adjustably moving said bearings to secure the desired tension, and means below said table to support said wire leaving the bottom of 40 said roll in a straight line without bends.

5. In a paper making machine the combination with a frame, of a table supported thereby, a wire passing over said table and back below it, a breast roll at the end of 45 said table, around which said wire passes, brackets secured to said frame at its end projecting longitudinally therefrom, and provided with longitudinal trackways, bearing blocks carrying said breast roll fitting 50 and movable along said trackways, and hand operated means on said brackets for moving said bearing blocks and breast rolls on said trackways to place proper tension on said wire.

In testimony whereof I affix my signature.

JAMES O'HARA.
